CLAIM

The ornamental design for a medical heat pad as shown and described.

DESCRIPTION

1. Medical heat pad

1.1 : Perspective

1.2 : Top

1.3 : Bottom

1.4 : Front

1.5 : Back

1.6 : Right

1.7 : Left

View 1.1 is a perspective view of the medical heat pad; View 1.2 is a top view thereof; View 1.3 is a bottom view thereof;

(Continued)

View 1.4 is a front view thereof; View 1.5 is a back view thereof; View 1.6 is a right view thereof; View 1.7 is a left view thereof.

1 Claim, 7 Drawing Sheets
